WILLIAM K. BLACK, OF PHILADELPHIA, PENNSYLVANIA.

Letters Patent No. 67,099, dated July 23, 1867.

IMPROVED SEWER-PIPE MACHINE.

The Schedule referred to in these Letters Patent and making part of the same.

TO ALL WHOM IT MAY CONCERN:

Be it known that I, WILLIAM K. BLACK, of the city and county of Philadelphia, and State of Pennsylvania, have invented a new and useful Improvement in Machines for Making Sewer Pipes; and I do hereby declare the following to be a full, clear, and exact description of the nature thereof, sufficient to enable others skilled in the art to which it appertains to fully understand and use the same, reference being had to the accompanying drawings, making part of this specification, in which—

Figure 1 is a front view of the device illustrating my invention, having the door of the cylinder opened, showing the internal parts of the cylinder.

Figure 2 is a longitudinal vertical section of the die taken through its middle.

Similar letters of reference indicate corresponding parts in the two figures.

This invention relates to that class of machines designed for manufacturing sewer pipes from clay or cement; and it consists, first, in suspending the knife and screw-shaft within the cylinder, whereby less power is required in pressing or forcing the clay through the die, and space is gained in the cylinder; secondly, in a removable funnel containing a suspended core-pin, whereby the die can be changed and others be substituted; thirdly, in constructing the portion of the shaft carrying the knives of wrought iron, and the screw or spiral flange and corresponding portion of the shaft of cast iron, so that the clay can be forced through the die, and the shaft be sufficiently strong to withstand the resistance offered by the clay during cutting and tempering; fourthly, in attaching a door to the cylinder by dividing the cylinder in two sections and hinging one to the other, which, when closed, forms a complete cylinder, and when opened admits of access to the die and the removal of stones and other obstructions which may lodge in the dies or within the cylinder.

In the drawings, A represents a horizontal frame, from which rise uprights A' connected by cross-pieces a b c. To the upper cross-piece c is secured lugs d, in which is mounted a horizontal shaft, e, carrying at one end a bevel-wheel, f, which meshes with a corresponding wheel, g, secured at the upper end of a vertical shaft, B. This shaft B is thus suspended from the wheel g, and has guide bearings in lugs or boxes, h i, secured to the cross-pieces b c respectively, and is constructed of wrought iron, having its lower end contracted, and provided with a screw-thread, k, into which fits a screw-socket on the upper part of the shaft C to which the screw or spiral flange D is secured. This shaft and flange are made of cast iron. It has been found that the great strain on cast-iron shafts, caused by the resistance of the shaft, will break or snap them, so that they must be replaced by new ones, and this is a common and expensive occurrence, and as the parts cannot be welded they are only useful as old iron. The shaft is again greatly weakened by the holes or openings made therein to receive the knives. I have endeavored to obviate this by constructing the portion of the shaft where such strain will be of wrought iron, and uniting it with the ordinary cast-iron spiral flange or screw by means of a socket and screw-joint or equivalents. This has proved from experience to be practical and useful, and will certainly remedy the evil spoken of. E is the cylinder, having on its upper end a flaring mouth or hopper, l. I cut the cylinder in two equal vertical sections, F F'. One portion, F', rests firmly on the cross-piece a, and the other portion is provided with hinges, m, whereby it will swing freely and admit of being opened and closed. Suitable hasps and staples are secured to the sections so that they will not open automatically. The bottom of the cylinder n has a circular opening, in which fits a ring, G, receiving in an opening in its centre the bottom of a funnel, H, which is readily removable. A longitudinal partition, o, is secured at the upper part of the funnel, from the lower side of the middle of which is suspended a core-pin, I, of conical form, whose bottom is flush with the funnel.

It will be seen that the die, consisting of the funnel and core-pin, rests firmly in position, but can be easily removed; and another one of a different size be substituted. The ring G can be made to have its central openings of various sizes, to correspond with the size of the bottom of the funnel. It will be only necessary to open the door or section F of the cylinder, and ready access is then had to the die. The suspended shaft leaves a space between its lower end and the top of the die, and by the simple arrangement of the die the clay is forced out almost uninterruptedly and without a loss of power. If stones should find a lodgment in the die, flange, or cylinder, and it be desired to remove them therefrom, ready access can be had thereto by merely opening the cylinder and digging out the obstruction, and on closing the same the machine can again be put in operation.

The shaft B is provided with the ordinary knives p, which cut and temper the clay, and the flanges or spirals force the clay through the die, forming a pipe at the bottom of the cylinder as the clay passes through the die.

The great disadvantage in the ordinary rising and falling flanges is the time required to return them to their highest points before a fresh supply of clay can be introduced into the cylinders. As the dies are to be removed often, it is evident that they should be clear of any connection with other parts of the machine. A suspended shaft only, having no bearing on the bottom of the cylinder, can be practically used for this purpose. The door must open entirely, from top to bottom of the cylinder, so that access can be had to any parts thereof, as well as to the die, which could not be removed if a mere hole or opening were made in the cylinder, or if the screw-shaft rested on the die.

Having thus described my invention, what I claim as new, and desire to secure by Letters Patent, is—

1. The revolving screw-shaft B C D, suspended from its bearings, when leaving a space between it and the bottom of the cylinder, as and for the purpose specified.
2. The construction of the shaft B of wrought iron, and the spiral flange D and shaft C of cast iron, forming the cutting, tempering, and forcing parts B C D, substantially as described for the purpose specified.
3. The suspended core-pin I, in combination with the funnel H, substantially as described for the purpose specified.
4. The removable ring G supporting the removable die H I, substantially as described.
5. In combination with the revolving screw, the door F of the sectional cylinder, extending from top to bottom thereof, for the purpose described and in the manner specified.

To the above I have signed my name this sixteenth day of April, 1867.

WM. K. BLACK.
